Inventor,
Henry Edward Hulseman

Att'y.

UNITED STATES PATENT OFFICE

HENRY EDWARD HULSEMAN, OF EVANSVILLE, INDIANA

LOOSE-LEAF BINDER

Application filed November 15, 1926. Serial No. 148,479.

My object is to provide improved clamping means for the covers of loose leaf binders, adapted for use in connection with a loose leaf binder of any type as, for instance, those which employ posts, and those having bands or loops on which the sheets are strung.

The present improvements, however, are not restricted to use in connection with the band or strap or post type of binder nor need 10 means be used for stringing the leaves, when my improvements are provided on the covers, inasmuch as I have found that the improved clamping devices comprising my invention are adapted to so firmly hold the covers in 15 their position that said covers may constitute the sole means for clamping the sheets, if a sufficient number of sheets are being held.

The invention comprises, in its broadest aspect, the provision of clamping pieces, 20 plates, members, or tongues on one of the cover sections, and eccentric clamps on the other section which are adapted to engage the members, clamping pieces, or tongues after the covers have been relatively ad- 25 justed.

In carrying out the invention, there may be provided two or more eccentric clamps which are independent of each other and co- 30 operate with the members or tongues afore- said, or, there may be two or more eccentrics carried by the same shaft or coupled together in any desired manner so as to be simultaneously operable.

Inasmuch as the invention is susceptible of 35 modification, I do not limit myself to the specific construction shown in the drawings nor to the details of construction and em- bodiments which are hereinafter described.

40 In the accompanying drawings:

Figure 1, is a plan view;
Fig. 2, is a longitudinal section;

Fig. 3, is a cross section; and

Fig. 4, is a detail perspective of the eccen- 45 tric locking lever.

The covers are shown at 1 and 2, each one carrying a suitable rigid clamp strip 3 be- 50 tween which the leaves are located.

As illustrated, the posts 4 may be used for stringing the leaves, or, straps or bands may 55 be employed for that purpose. My invention

is not limited to the particular means em- 55 ployed for stringing the leaves. Indeed, it is not necessary that any means be provided for stringing the leaves if a sufficient number of the leaves be employed to enable the clamping strips to bear on them, as I find in practice that it is possible to entirely dis- 60 pense with posts, bands, or other means for stringing the leaves.

In carrying out my invention I secure to 65 one of the clamping strips or plates 3, two or more clamping members, tongues, or pieces 5 which are of sheet metal, preferably of considerable rigidity. The length of the outstanding parts of these members or 70 tongues determines the extent to which the binder may be extended. I do not restrict the invention to the use of rigid clamping members or tongues 5 as it may be possible to employ pliable or bendable metallic strips 75 instead of rigid strips for that purpose.

Carried by the other strip 3 are guides or 80 receivers 6 which may be constructed as illustrated or assume other forms. As shown, these guides or receivers 6 have eyes 7 spaced 75 apart slightly further than the width of the tongues or members 5, the latter passing be- 85 tween said eyes.

Journaled in the eyes are independent 85 eccentric or cam levers 8 which are provided with handles 9. These eccentric levers have their shafts cut away so that when the cut- 90 away parts 10 are located opposite the tongues 5, the tongues may be freely slid to expand or contract the binder. When, how- 95 ever, the handles are turned to bring the eccentric parts 11 against the tongues, the tongues are securely clamped.

I wish it understood that my invention 95 comprehends any kind of an eccentric or cam device for clamping the tongues 5 and is not limited to the specific construction shown. Furthermore, the guide plates or receivers 6 may be constructed quite differently from the form shown.

The two eccentric clamps may be coupled, or formed, or provided on a single rod instead of on two rods, as shown, and said single rod may have either one or two 100 handles. It is also within the spirit of my

invention to provide a series of cams or eccentrics and a series of tongues and guides. In very large binders it may be necessary to employ a number of eccentrics, whether they be coupled together, or be adapted for independent operation.

The tongues or pieces 5 may be corrugated and the parts 9 may be of round constructions, with a small removable head, if desired. In that event, the said removable head may be taken off of each of the parts 9 and the binder used as a permanent binder, if desired, ready to be filed away permanently.

What I claim is:

15 1. A loose leaf binder comprising covers each having a rigid elongated angle member rigidly attached to the cover and freely movable toward and away from each other and adapted to directly clamp any desired number of the sheets therebetween, and means for locking the said angle members in any desired expanded or contracted relationship to each other solely comprising tongues which may be freely slid in either 20 direction when free, and releasable means adapted to bind directly on the tongues for clamping or releasing the same.

2. A loose leaf binder comprising covers each having a rigid elongated angle member having one of its sides rigidly attached to the cover and freely movable toward and away from each other and adapted to directly clamp any desired number of the sheets therebetween, and means for locking the said 30 angle members in any desired expanded or contracted relationship to each other solely comprising tongues carried by one of the angle members and freely slidable in either direction toward or away from the other angle member when free, and releasable means on the other angle member adapted to bind directly on the tongues for locking the same wherever they are adjusted.

3. A loose leaf binder comprising relatively extensible covers each having an angle member, one of whose sides lies flatwise against, and is secured directly to, said covers and, in addition thereto, one of the angle members being provided with locking members 45 projecting therefrom, guides or receivers carried by the angle members on the other cover and serving to receive the aforesaid locking members, and locking devices carried by the last-named cover which have 50 their axes extending crosswise of said locking members when the latter are in the guides or receivers, said locking devices being adapted to bind directly on the locking members.

60 4. A loose leaf binder comprising relatively extensible covers each having an angle member, one of whose sides lies flatwise against, and is secured directly to, a cover and, in addition thereto, one of the angle 65 plates being provided with flat locking mem-

bers projecting freely therefrom, guides or receivers carried by the angle member on the other cover and serving to receive the aforesaid members, and rockable elongated locking cams carried by the last-named cover, which have their axes extending crosswise of said locking members when the latter are received in the guides, said locking cams being mounted on the guides or receivers and adapted to bind directly on the flat locking members.

5. A loose leaf binder comprising relatively extensible covers, each having an angle member, one of whose sides lies flatwise against, and is secured directly to a cover and, in addition thereto, one of the angle members being provided with cross-sectionally flat locking members projecting freely in a direction substantially parallel to the plane of the back of said binder, flat guide members carried by the other cover and provided with eyes which are spaced apart a distance sufficient to permit the locking members to slide therebetween, and rockable cams each comprising an elongated shank mounted to turn in said eyes and a flattened part arranged over the locking members, and means for turning said cams, whereby they may be made to directly bind on, or to release, said flat locking members.

In testimony whereof I affix my signature

HENRY EDWARD HULSEMAN.
